UNITED STATES PATENT OFFICE.

EDWARD W. SPRAGUE, OF CENTRAL SQUARE, NEW YORK.

NUT-LOCK.

SPECIFICATION forming part of Letters Patent No. 447,703, dated March 3, 1891.

Application filed April 19, 1889. Serial No. 307,669. (Model.)

To all whom it may concern:

Be it known that I, EDWARD W. SPRAGUE, of Central Square, county of Oswego, in the State of New York, a citizen of the United States, have invented certain new and useful Improvement in Nut-Locks, of which the following is a specification, reference being had to the accompanying drawings, in which—

Figure 1 is a side elevation of the rail, showing the nut-lock in position. Fig. 2 is a view of the first section 4 detached. Fig. 3 is a similar view of the second section 5; and Figs. 4 and 5 are rear views of the sections 4 5, respectively.

15 My invention relates to devices for locking the nuts upon the bolts which secure the fish-plates in place upon the joints of railway-rails.

20 My object is to provide a nut-lock for fish-plates which is adapted to give the expansion and contraction of the rails, as well as to hold the nuts upon the bolts, and which can be readily applied and taken off.

25 My invention consists in the several novel features of construction and operation hereinafter described, and which are specifically set forth in the claims annexed. It is constructed as follows:

30 A represents a railway-rail meeting another rail at 1.

B is the fish-plate of any desired construction, and 2 2 the bolts holding the rails and fish-plates together by the nuts 3, either square or hexagonal.

35 C is the nut-lock, consisting of the sections 4 5, both of them constructed from flat metal bars, the one 4 provided with notches 6 to fit over the nut, with an elongated bolt-hole 7 adjacent to one end, and a shoulder 8, riding 40 above the plane of that part adjacent to the bolt-hole 7 and upon the other end and upon the inner face provided with serrations 9. The other section 5 is also provided with the notch 6 to fit over the nut, a bolt-hole 10, and

45 a projecting beveled lip or lips 11, fitting the serrations 9, and with a shoulder 12 standing above the plane of that portion adjacent to the bolt-hole 10. To put this together, I screw up the bolts on the left tightly, or nearly 50 tight as to the outer one, the bolt fitting

through the slot 7 at its outer end, the plate-section then standing nearly in a vertical position, so that when I then throw this section down to a horizontal, after driving it until the bolt is in or adjacent to the right-hand end 55 of the bolt-hole 7 and the nut is close to or against the shoulder 8, the slotway 6 will slip over the bolts on either side of the joint between the rails, and this throwing down of this section will turn the end bolt sufficiently 60 tight, and this section 4 will lie tightly against the fish-plate. The section 5 fits over the bolt on the right after that is screwed up, and the next bolt passes through the bolt-hole 10 and the serrations 9 fit into or over 65 the lip or lips 11, and the nut upon the bolt passing through the slot 10 will rest against the shoulder 12 or sufficiently close thereto, so that it cannot turn to any extent. A lug 70 13 can be used upon the innerface of the section 5 at the top edge, fitting under the thread of the rail when horizontal, or when vertical can fit over the end of the fish-plate. It will thus be seen that the fish-plates being constructed with elongated bolt-holes to permit 75 of the expansion and contraction of the rails when the rails expand the nut-lock sections will slide upon each other at their meeting-points where the serrations meet each other without causing any strain upon either 80 of the nuts, and that also all of the nuts will be held and locked against becoming loosened.

What I claim is—

1. The combination, with the fish-plates and 85 the securing bolts and nuts, of a locking-bar constructed in sections, the outer ends of the sections fitting over the securing-bolt and having a shoulder bearing against the nut thereon and provided with an edge notch fitting over the nut on the inner securing-bolt, one section having serrations upon its inner end and the other having like serrations locking into those on the other sections, as set forth. 90

2. The combination, with the fish-plates and 95 the securing bolts and nuts, of a nut-locking bar constructed in sections, the outer ends of both sections being pivotally mounted upon the outer securing-bolts and each having a shoulder bearing against the nut upon the 100

securing-bolt and each section being notched to fit over the nuts on the intermediate bolts, one section having serrated teeth upon its inner end and the other having serrated recesses adapted to engage with the teeth.

3. A fish-plate nut-lock consisting of two bars notched to fit over the nuts, the one being provided with serrations 9 and the other with

beveled lip or lips 11, substantially as described.

In witness whereof I have hereunto set my hand this 15th day of April, 1889.

EDWARD W. SPRAGUE.

In presence of—

H. P. DENISON,
F. T. DENISON.
